CLAIM

The ornamental design for a hoof cleaning tool, as shown and described.

DESCRIPTION

FIG. 1 is a perspective view of a front, top, and first side of an ornamental design for a hoof cleaning tool showing bristles thereof in broken lines;

FIG. 2 is an elevational view of a second side of the hoof cleaning tool of FIG. 1;

FIG. 3 is an elevational view of the first side of the hoof cleaning tool of FIG. 1;

FIG. 4 is a front elevational view of the hoof cleaning tool of FIG. 1;

FIG. 5 is a rear elevational view of the hoof cleaning tool of FIG. 1; and,

FIG. 6 is a top plan view of the hoof cleaning tool of FIG. 1. Broken lines and portions contained within broken lines are not claimed.

1 Claim, 3 Drawing Sheets
